Patented Jan. 3, 1922.

UNITED STATES PATENT OFFICE.

HAROLD LORAH BUMBAUGH, OF STANFORD UNIVERSITY, CALIFORNIA.

VAPORIZER.

1,402,715.

Specification of Letters Patent.

Patented Jan. 3, 1922.

Application filed November 30, 1920. Serial No. 427,450.

To all whom it may concern:

Be it known that I, HAROLD L. BUMBAUGH, a citizen of the United States, and resident of Stanford University, county of Santa

5 Clara, and State of California, have invented a new and Improved Vaporizer, of which the following is a full, clear, and exact description.

My invention relates to a vaporizer, and 10 aims to provide a device of this character which shall provide an extremely combustible mixture for a consuming element, and is particularly intended for use in connection with the latter at the time of starting.

15 In connection with the consuming elements utilizing volatile fuels, and more particularly internal combustion engines, it is well appreciated that considerable difficulty has been experienced in that an excessive 20 drain has been thrown upon the starting battery where this was used, incident to the utilization of the starting motor for cranking the engine.

This is particularly true where the engine 25 is entirely cold. It is also well understood, that it is necessary at the time of starting the motor, to utilize what is commonly termed a "choke," which results in an extremely rich fuel mixture flowing through 30 the manifold into the cylinders, so as to produce an initial explosion, as is usually the case where the engine does not take hold immediately, a certain amount of the rich mixture flows past the pistons and so into the 35 crank case where it results in a diluting of the oil, causing a rapid wearing away of the parts lubricated by the oil. This is also the case where "priming" is resorted to, and in this latter instance, the conditions are often 40 found to be far more aggravated than is the case where merely the choke is resorted to.

Also where numerous starts are resorted to, a great amount of fuel is wasted, incident to the extremely rich mixture utilized, which 45 will result in the well known defects of carbon, and general inefficiency of operation, aside from the expense involved.

It will further be understood that considerable difficulty has been experienced in 50 that a carburetor may be set to a certain adjustment to meet certain requirements of temperature, mixture, etc., and that subsequently, upon the temperature dropping that the motor will be extremely difficult to start, 55 even although the choke should be utilized to the fullest extent.

With this in view, I have constructed a vaporizer which will permit of practically the instantaneous starting of the consuming element, such as an explosive motor, so that 60 it will be only necessary to actuate the starting crank to an extremely small extent, or in case a starter is used, the same will be operated for merely a proportionate amount of time to produce an initial explosion, thus 65 saving the battery from the terrific drainage and distortion of the plates incident to a continued operation of the starting motor.

A further object of my invention is the construction of a device of this nature, which 70 will prepare and permit of the feeding of just sufficient fuel to the motor in the form of a high explosive gas, to permit of the production of the initial explosion.

A still further object of my invention is 75 the construction of a vaporizer in which no unused gas in liquid form remains in the cylinders, so that the defects incident to this procedure will be eliminated.

Another object of my invention is the construction of a vaporizer which will operate regardless of the specific gravity of the fuel, or of atmospheric temperature or conditions.

Still another object of my invention is the provision of a device which will permit of 85 the carburetor being set to produce an extremely lean mixture, in that the vaporizer will provide a medium for producing an initial operation, thus permitting an operator to dispense with a rich adjustment of the 90 carburetor.

Still further objects of my invention are the provision of a vaporizer which shall be extremely simple in construction and operation, and in which no adjustment will be required, so that the same may be readily produced, operated and installed. 95

Reference is had to the attached sheet of drawings as illustrating one practical embodiment of my invention, and in which— 100

Figure 1 is a somewhat diagrammatic view of a vaporizer constructed in accordance with my invention, and showing the same associated with a consuming element in the form of an internal combustion engine, 105 and

Figure 2 illustrates the moving part of the vaporizer in a position different from that illustrated in Figure 1.

In these views the reference numeral 5 110 indicates the intake manifold, of an internal combustion engine with which a vaporizer,

including a casing 6 is connected by any suitable means such as a tube 7.

5 A secondary tube 8 also connects with the casing 6, and is provided with a valve 9, of any suitable character, adapted to be operated by means of a throw lever 10, normally held in the position illustrated in full lines 10 in Figure 1, by means of a spring 11, or other suitable means, whereby the valve 9 is normally retained in closed position.

Further, a cable or other suitable element 12 has one of its ends connected to the outer 15 end of the throw lever 10, the opposite end of the same conveniently passing over the pulley 13, and being connected by any suitable form of hand pull 14, preferably presented upon the dash 15.

20 Thus upon a pull being exerted upon the hand pull 14, the cable 12 will cause the throw lever 10 to be moved upwardly to the position indicated in dotted lines in Figure 1, and full lines in Figure 2, causing the 25 valve 9 to open, as has been shown in Figure 2.

Arranged within the casing 6 and preferably at a point directly under-lying the inner end of the tube 8, is a heating medium 30 such as a coil 16, which coil is conveniently mounted in series with a terminal 17, and a contact terminal 18. A secondary terminal 19 serves to afford a "ground" for a purpose hereinafter more fully specified.

35 Now it will be seen, assuming that the tube 8 is connected to a suitable source of fuel supply, that when it is desired to start a consuming element, that this may readily be accomplished by opening the valve in the 40 manner specified. It will also be seen that the inner end of the throw lever 10 is provided with a contact strip 20, which when the lever is moved to the position indicated in dotted lines in Figure 1, will bear against 45 the contact terminal 18, as has been clearly shown in Figure 2.

This will result in a closing of the circuit in that the terminal 19 is grounded, which will permit the current to flow through the 50 throw lever 10 to the tube 8, and thus to the casing 6 to which the grounded terminal is affixed.

By virtue of the fact that the heating element 16 directly underlies the inner end of the tube 8 it will be appreciated that the fuel introduced into the casing therethrough will be vaporized, and form a mixture within the casing, which mixture will be of a highly explosive nature.

This mixture will pass through the tube 7 60 and flow into the fuel intake manifold, so that the slightest actuation of the consuming element, such as a cranking of the same, will result in this highly explosive mixture being 65 drawn into the cylinders, where upon being subjected to the action of a spark plug, it will instantly produce the initial explosion.

Obviously this will be accomplished in an extremely short period, and upon the fuel mixture being subjected to the spark action, 70 it will be appreciated that an instantaneous explosion, will result, thereby starting the consuming element.

Thus I have constructed a vaporizer in which no continued cranking is necessary, 75 so that the defects incident to this operation as aforesaid will be eliminated.

It will further be seen that the motor will draw just sufficient fuel in the form of hot explosive gas to meet the requirements incident to producing the initial explosion, and also that no unused gas in liquid form will remain in the cylinders, as will result, in the case of "priming" or utilization of the "choke." 85

Also it will be seen that all of the objects enumerated in the preamble to this specification will be accomplished.

Obviously numerous modifications of structure might readily be resorted to without in 90 the least departing from the spirit of my invention, which I claim as—

1. A vaporizer, including a casing, an intake tube connected to said casing, an outlet tube also connected to said casing, a valve 95 within said first named tube, an electric heating element within said casing, and a throw lever connected to said valve for actuating the same, said throw lever being adapted, upon moving said valve to its open 100 position, to close the circuit through said heating element to actuate the same.

2. A vaporizer, including a casing, an electric heating element within said casing, a contact point connected to one of the ends 105 of said heating element, one of the terminals of a source of current connected to the opposite end thereof, a pair of tubes connected to said casing, a valve interposed in one of said tubes, a throw lever connected to said valve for permitting an operation of the same, said throw lever being adapted to engage said contact point when the valve is in open position to close the circuit through the heating element. 110

HAROLD LORAH BUMBAUGH.
